US0D1113486S

(12) **United States Design Patent** (10) **Patent No.:** **US D1,113,486 S**
(45) **Date of Patent:** **** Feb. 17, 2026**

(54) **TEMPERATURE AND HUMIDITY RECORDER**

(71) Applicant: **Jiangsu Jingchuang Electronics Co., Ltd.**, Xuzhou (CN)

(72) Inventors: **Changdong Chen**, Jiangsu (CN); **Chaofei Li**, Jiangsu (CN)

(**) Term: **15 Years**

(21) Appl. No.: **35/521,842**

(22) Filed: **May 20, 2024**

(80) **Hague Agreement Data**

Int. Filing Date: **May 20, 2024**

Int. Reg. No.: **DM/238574**

Int. Reg. Date: **May 20, 2024**

Int. Reg. Pub. Date: **Aug. 2, 2024**

(30) **Foreign Application Priority Data**

Nov. 24, 2023 (CN) 202330770263.0

(51) **LOC (15) Cl.** **10-04**

(52) **U.S. Cl.**

USPC **D10/52**; D10/57; D10/56

(57)

CLAIM

The ornamental design for a temperature and humidity recorder as shown and described.

DESCRIPTION

1. Temperature and humidity recorder

1.1 : Top

1.2 : Front

1.3 : Left

1.4 : Right

1.5 : Bottom

1.6 : Rear

1.7 : Perspective

1.8 : Perspective

The broken lines in the drawings depict portions of the temperature and humidity recorder that form no part of the claimed design.

1 Claim, 8 Drawing Sheets
